Primary Examiner — Marcus Jackson(74) *Attorney, Agent, or Firm* — GTC Law Group LLP & Affiliates(57) **CLAIM**

The ornamental design for an inductive lamp, as shown and described.

DESCRIPTION

FIG. 1 is a front elevation view of an inductive lamp depicting the upper and lower portions of our new design, the upper portion made of a translucent glass material with an appearance of frosted glass or glass coated with a light-diffusing material, and the lower portion made of an opaque plastic material;

FIG. 2 is a top plan view thereof; and,

FIG. 3 is a bottom plan view thereof.

The broken lines in FIGS. 1-3 are for environmental purposes only and form no part of the claimed design. No particular color scheme forms part of the claimed design.
